HOLDER FOR BEER FOAM SCRAPERS OR THE LIKE

Harold Austin, New York, N.Y., assignor to The F. & M.
Schaefer Brewing Co., Brooklyn, N.Y.

Filed Feb. 6, 1961, Ser. No. 63,830

Term of patent 14 years

(Cl. D2—3)

FIG 1

FIG 3

FIG. 4

FIG. 5

FIG. 6

FIG. 1 is a front elevation of the holder for beer foam scrapers or the like showing my new design;

FIG. 2 is a top plan view of the holder of FIG. 1;

FIG. 3 is an end elevation of the holder of FIG. 1;

FIG. 4 is a rear elevation of the holder of FIG. 1;

FIG. 5 is a bottom plan view of the holder of FIG. 1. FIG. 6 is a vertical section taken on the line 6—6 of FIG. 2 in the direction of the arrows.

FIGS. 1, 3 and 4 of the drawing are lined to indicate rows of fine parallel score lines.

I claim:

The ornamental design for a holder for beer foam scrapers or the like as shown and described.
